WINDOW LOCK

Fritz F. Larson, St. Paul, Minn.

Application April 4, 1938, Serial No. 199,985

4 Claims. (Cl. 292—152)

This invention relates to window locks and more particularly to a device of this character which may be applied either to multiple sash or single sash sliding window structures to lock the sashes in either closed or partially open position.

The invention has for its principal object to improve generally upon window locking devices and to produce a simple yet strong and durable structure which is readily applied and adjusted.

Other and more specific objects to be attained will hereinafter more fully appear.

The invention consists in the general structure and in the particular parts and combinations and arrangements of parts thereof as hereinafter described and set forth in the appended claims, reference being had to the accompanying drawing forming a part of this specification, and in which

Figure 1 is a fragmentary view showing the meeting corner portions of an upper and lower window sash with the locking device applied thereto;

Figure 2 is a section, on an enlarged scale, taken on or about the line 2—2 of Figure 1;

Figure 3 is a cross section through the bolt element and adjacent portion of the housing, taken on or about the line 3—3 of Figure 2; and

Figure 4 is a section on the line 4—4 of Figure 2.

Referring now to the drawing the numeral 10 designates the upper sash of a window and the numeral 11 designates the lower sash thereof, said sashes being of the usual vertical sliding type.

On the inner face of one of the vertical side rails of the sash frame is a rack plate 12, said plate being corrugated transversely or otherwise formed to produce the multiplicity of teeth 13 thereon, and the plate being secured to the sash rail by ordinary wood screws 14. Mounted on the top of the lower sash is a cylindrical bolt housing 15 having longitudinal base flanges 16 on opposite sides thereof, said base flanges being secured to the sash 11 by screws 17. As shown, the longitudinal side flanges 16 merge at their rear ends with a transverse base flange extension 18 whose rear end portion 19 is turned downwardly over the rear edge portion of the sash 11 as shown more clearly in Figure 2.

Located within the cylindrical housing 15 is a latch bolt 20 of general cylindrical form, the main body portion of which may be either solid or hollow. As shown, the bolt 20 has a cy-

lindrical enlargement or head portion 21 at its rear end which is of a diameter to fit slidably within the cylinder 15, while the extreme end portion of the head 21 is squared, as at 22, and provided on its outer face with a multiplicity of teeth or corrugations 23 to fit and interlock with the teeth 13 of said rack plate 12 on the upper sash 10.

Surrounding the reduced body or shank portion 20 of the bolt within the cylindrical housing 15 is a coil spring 24, one end of which abuts the annular shoulder formed by the cylindrical enlargement or head portion 21 of the bolt, and the opposite end of the spring abutting a longitudinally adjustable plate 25 which is located in the outer end portion of the housing 15 and held by an adjusting screw 26 provided in a cap member 27 secured on the forwardly projecting end portion 28 of the housing. By the foregoing construction and arrangement the latch bolt is normally urged into interlocking engagement with said rack plate 12 and the tension of the spring 24 is regulated by adjusting the screw 26, and in this connection it is noted that the downturned flange portion 19 of the rear base flange 18 of the cylindrical housing 15 affords an ample end thrust support for said housing against the reactive force of the spring 24.

To retract the bolt an operating lever 29 is pivotally mounted, as at 30, between a pair of 30 upstanding ears 31 at the rear end of the cylindrical housing 15, said lever 29 having an angular extension 32 at its rear end which engages in a socket 33 in the adjacent upper portion of the head 21 of said bolt element 20, the main 35 arm of said lever extending forwardly beyond the end of the housing 15 and having an upstanding manipulating knob or handle member 34 thereon, while at the extreme end of said lever 29 is an arcuate downward extension 35 provided on its circumferential portion with an upper series of ratchet teeth 36 and a lower series of reversely shouldered similar teeth 37. By manipulating the lever 29, that is to say, by raising the forward portion of said lever the rear 45 angular arm 32 thereof is swung forwardly and moves the latch bolt a corresponding distance forwardly in said housing 15 and against the tension of the spring 24, and to releasably lock said lever 29 so as to hold the latch bolt 20 retracted the end cap member 27 is provided with a forwardly extending resilient arm 38 having an up-turned outer end extension 39 provided at its extreme end portion with a pair of opposed teeth 40, 41 which are normally held in engag- 55

ing relation to the ratchet teeth 36 or 37, by the inherent resiliency of the member 39, which latter is provided with a knob or handle member 42 by which said member 39 may be moved to release said teeth 40 and 41 from said ratchet teeth 36 and 37, at will.

Preferably, a guard or guide for said lever 29 is provided, as shown in Figures 2 and 4, said guard comprising a single piece of sheet material bent upon itself to provide opposed spaced side plates 43 between which the lever 29 extends forwardly from its pivot 30 and the looped connecting portion 44 between said plates 43 being at sufficient height to permit ample vertical swing of said lever 29, said plate portions 43 each having a pair of arcuate tongue portions 45 extending around the adjacent opposite side portions of said cylindrical bolt housing 15 and secured rigidly thereto by welding or any other approved method of fastening.

By the foregoing, it is noted that a secure sash lock is provided whereby the sash may be locked either in closed or partially opened position and that in the case of its application to cooperating upper and lower sashes as shown in the drawing and the lock set to hold the sash in partially opened position either the lower sash may be raised to the limit set by the lock or the upper sash accordingly lowered, that is to say, the two sashes move together in either direction. So, too, it is obvious that the device may be applied to single sashes, in which case the rack plate 12 may be mounted on the sash frame and the latch bolt housing 15 located on the window frame. In any case, the bolt 20 is held in locking relation to the rack plate 12 by the engagement of the tooth 41 on the member 39 with the arcuate series of ratchet teeth 36 and in retracted position by the engagement of the tooth 40 on said member 39 with the other arcuate series of ratchet teeth 37, while at the same time the tension of the spring 24 may be varied by adjusting the screw element 26.

Obviously, the structure admits of considerable modification within the spirit of the invention as defined by the appended claims. The invention, therefore, is not limited to the specific construction shown in the accompanying drawing.

What is claimed is:

- 50 1. A window lock comprising a bolt housing, a spring-pressed bolt in said housing normally urged into engaging relation with a detached keeper element, a lever element cooperatively engaged with said bolt for retracting the latter, said lever element having an arcuate free end portion provided with two series of oppositely directed ratchet teeth, and a latching extension on said bolt housing having provision for interlocking ratchet engagement alternatively with the two series of teeth on said lever element whereby to lock the bolt in extended or retracted position, at will.
- 55 2. A window lock comprising a cylindrical bolt housing having base flanges at its opposite sides for the mounting thereof and an end base flange formed with an angular end thrust abutment, a spring-pressed bolt element in said housing, said bolt element having its keeper-engaging end portion normally urged beyond the end base flange of the housing, an operating lever mounted on said housing and having an angular extension engaging in a socket provided therefor in said bolt element, said operating lever extending beyond the opposite end of said bolt housing, the 70 free end portion of the lever having a manipu-

lating handle and an arcuate extension provided with two series of oppositely directed ratchet teeth, and a releasable latch element on said bolt housing having an opposed pair of teeth respectively engageable with one of the series of ratchet teeth of said operating lever whereby to hold said bolt element in extended or retracted position, at will.

3. A window lock comprising a cylindrical bolt housing having base flanges for the mounting thereof, a bolt element having a cylindrical head portion working in said housing, said head portion extending beyond the adjacent end of the housing and provided at its extreme end portion with keeper-engaging means, the inner end of 15 the head providing an annular spring-receiving shoulder, a spring element surrounding said bolt element and bearing against said spring-receiving shoulder for normally urging said bolt element with its keeper-engaging end portion projected from the bolt housing, an operating lever pivotally mounted on the bolt housing adjacent the end thereof and having an angular extension engaging in a socket provided therefor in the head portion of said bolt element, said lever 20 extending beyond the opposite end of the housing and provided with a manipulating handle and an arcuate ratchet extension, a cap member on the adjacent end portion of the bolt housing provided with a resilient arm extending longitudinally therefrom and formed with an angular extension, said angular extension having a toothed portion engageable with the arcuate ratchet extension of said operating lever, and a manipulating knob on said resilient arm extension for 30 springing said extension to disengage the toothed portion thereof from said ratchet extension of the lever.

4. A window lock comprising a latch bolt housing including a cylindrical body portion open 40 at its inner end and provided at its outer end with a cap member, a generally cylindrical bolt element of smaller diameter in said cylindrical body portion, said bolt element having a cylindrical head enlargement adjacent its outer end 45 fitted slidably to the cylindrical body portion of the bolt housing and formed with a rectangular extreme outer end portion having keeper-engaging provision on its outer face and its bottom edge portion being slidable upon a rear base 50 flange portion of the bolt housing body, the inner end of said cylindrical head providing an annular spring-receiving shoulder, a longitudinally adjustable abutment within said housing adjacent said end cap member thereof, an axial adjusting 55 screw on said cap member in cooperative relation to said abutment member, a spring element coiled about said bolt element and interposed between said longitudinally adjustable abutment and the shouldered head portion of the bolt element, an operating lever pivotally mounted at its inner end between an upstanding pair of ears provided therefor on the adjacent inner end portion of the housing body cylinder, said lever having an angular extension cooperatively engaged in a socket provided therefor in the adjacent head portion of said bolt element, said operating lever extending forwardly beyond the outer end of said housing body cylinder, and means for releasably locking said operating lever in different actuated positions for holding the bolt element in extended keeper-engaging and retracted keeper-disengaged positions.
